ELECTRIC PLUG

Morris Kaplan, Chicago, Ill.

Application March 20, 1946, Serial No. 655,678

3 Claims. (Cl. 173—328)

1

The present invention relates to electrical connectors, and more particularly to those of the plug-in type.

It is an object of the present invention to provide a plug-in connector which may be utilized with sockets of the type used on automobile dashboards, such as cigarette lighter sockets, for instance. By the use of such a plug electrical connection may be made from the socket to some electrical instrument, such as a portable trouble light, for instance.

It is a further object of the invention to provide such a plug connector which is compact, is easily assembled, is sturdy, and which operates satisfactorily.

It is a still further object of the invention to provide a plug connector which may be used in combination with standard sockets.

The attainment of the above and further objects of the present invention will be apparent from the following specification taken in conjunction with the accompanying drawing forming a part thereof.

In the drawing:

Figure 1 is a longitudinal sectional view of the plug embodying the invention, shown in combination with a socket with which it is utilized;

Figure 2 is an end view of the plug shown in Figure 1, looking in the direction of the lines 2—2;

Figure 3 is a front view, disassembled, of one of the elements of the plug;

Figure 4 is a front view, disassembled, on an insulation element of the plug;

Figure 5 is a side view of Figure 4, looking in the direction of the lines 5—5;

Figure 6 is a front view, disassembled, of another element forming part of the plug; and

Figure 7 is a front view, disassembled, of one of the electrical connector members.

In describing the plug embodying the invention it is deemed advisable first to describe, briefly, a conventional automobile cigarette lighter socket with which it is utilized in combination. The socket comprises an outer metallic casing 11 having three circumferentially spaced cut-out portions 12 and a screw threaded hollow post 13 at the extremity thereof. The cut-out portions 12 are formed at the top (or right, Fig. 1) with two short slots (not shown), separated by a short spring lug 15 which extends a short distance within the casing 11, for a purpose to be described hereinafter. A plastic cap or cylinder 14 surrounds the casing 11 at the forward, or right (Fig. 1) end thereof. A metal cap 16 having a

2

member which is screw threaded at 17 is secured thereto, the screw internally threaded sleeve 17 threaded on the post 13. The cap 16 extends forwardly, when tightened in place, until its front edge engages the rearward end of the plastic cylinder 14.

A threaded terminal screw 18 extends within the central opening of the post 13, separated therefrom by an insulator tube 19, and terminates in a headed portion to which is secured three uniformly spaced metallic spring clips 21, extending forwardly in the casing 11. A metal clip 22 having outwardly extending lugs surrounds the screw 18 with the lugs entering depressions in a plastic insulator 23, thus insuring against movement of the elements. The insulator 23 prevents the spring clips 21 from engaging the casing 11. An insulation washer 24 prevents the clips 22 from engaging the post 13. It should be noted that the cut-out portions 12 in the casing 11 are adjacent the spring clips 21, so that the latter cannot engage the casing 11.

A nut 26 engages the screw threaded extremity of the screw 18 and is separated from the end of the post 13 by an insulating washer 27. The screw 18 receives the end terminal of a conductor leading from a suitable current source. The current will thus be conducted through the screw 18 to the head thereof and to the spring clips 21. Only one terminal is necessary as the electrical circuit may be completed through grounding at some convenient point.

The plug connector embodying the invention comprises a plastic handle 31 having a central opening and a screw threaded extremity 32. A plastic cylinder 33, internally threaded, engages the threaded portion 32. An electrical extension cord 34 extends through the central opening of the handle 31 to some external operating unit, such as a portable trouble light.

A metallic grounding cap 36 is screw threaded into the connecting cylinder 33. The cap 36 may be seen more clearly in Figure 3, which is a view showing the cap 36, looking at the side opposite from the threaded portion. The cap 36 has a central opening 37 and two arcuate slots 38. When in proper position the cap 36 engages the short spring lugs 15 of the casing 11.

An insulation member 39, seen more clearly in Figures 4 and 5, also having a central opening and arcuate slots or troughs 41, is so shaped as to engage the cap 36 with the slots 38 and the troughs 41 aligning. Such alignment is achieved through arcuate shoulder portions 40 on one side 55 of the member 39, which shoulder portions ex-

tend part way into the arcuate slots 38 of the cap 36. A pair of small rectangular openings or slots 42 extend completely through the insulation member 39.

A metallic end cap 43, more clearly seen in Figure 6, is provided with a smoothly curved peripherally extending overhanging ring portion 44. The cap 43 is likewise provided with a central opening and with arcuate slots 46, the latter extending through the cap and coinciding with the arcuate depressions 41 in the member 39.

A large-headed threaded bolt 47 extends through the central openings in the metallic cap 36, the insulation member 39, and the metallic end cap 43, a nut 48 engaging the threaded portion. An L-shaped electrical connector lug 49, seen more clearly in Figure 7, and likewise having a central opening to receive the bolt 47, is positioned between the nut 48 and the metallic cap 36. One of the terminals of the cord 34 is secured by suitable means, such as soldering, to an extending prong of the connector 49.

As previously mentioned, the insulation member 39 engages the cap 36 and separates it from the metallic end cap 43. An insulation tube 51 surrounds the shank of the bolt 47 and extends through the central openings of the cap 36, the member 39, and the end cap 43.

A second electrical connector lug 52 having a central opening to receive the bolt 47 is positioned in engagement with the end cap 43 on the side away from the member 39. The insulator 51 extends within the central opening of the connector 52 also, thus preventing it from engaging the bolt 47. An insulating washer 53 separates the connector 52 from the head of the bolt 47. The connector 52 is provided with a relatively long prong 54 which extends through one of the arcuate slots 46 of the end cap 43 and through a rectangular slot 42 of the insulation member 39, and through one of the arcuate slots 38 of the cap 36. The second wire of the cord 34 is secured to the prong in any convenient manner, as by soldering. An electrical circuit may thus be extended from the prong 54 of the connector 52 to the end cap 43 with which it is in engagement. As the arcuate shoulders 40 of the insulation member 39 enter the slots 38 of the cap 36, and as the prong 54 passes through the rectangular slot 42, it is impossible for the prong 54 to short-circuit against the cap 36.

The positioning of the various members and the tightening of the bolt 48 on the bolt 47 will insure that the parts will be held firmly in place.

When the plug is inserted in the socket, initially described, battery potential is thus extended from the socket spring clips 21, through the lip or overhanging portion 44 of the end cap 43 which engages them, through the end cap 43, through the electrical connector 52 with which it is in engagement, and over the connector prong 54 to one terminal of the cord 34.

It is to be remembered that the current source had only one terminal, the circuit being conveniently grounded. The ground for the external apparatus may be established through the other terminal of the cord 34, through the prong and electrical connector 49, and through the cap 36 with which it is in engagement, to the spring lugs 15 and the casing 11 which is grounded.

Once the plug has been inserted in the socket the spring clips 21 engaging the overhanging portion 44 of the end cap 43 will act to hold it secure, whereas the cap 36 engaging the short spring lugs 15 of the casing 11 will prevent any un-

desired sideward movement. The plug is easily detached by slight pulling pressure on the handle 31.

While a specific embodiment of the invention has been illustrated and described, it is to be understood that the invention is not limited thereto but that such is only illustrative of the principles of the invention.

What is claimed is:

1. In a plug connector, a handle of insulating material having a central opening to receive an extension cord, a metallic grounding cap having a central opening therein and opposed arcuate slots therein, means to connect said handle and said grounding cap, an insulating member having arcuate troughs extending part way therethrough, small rectangular slots extending all the way therethrough, and arcuate shoulder portions adjacent said grounding cap, said shoulder portions extending within the arcuate slots in said grounding cap, an end cap having arcuate slots adjacent said insulating member, an electrical connector for joining one terminal of said extension cord to said metallic grounding cap, a second electrical connector for joining the second terminal of said extension cord to said end cap, said second connector extending through an arcuate slot in said metallic grounding cap, the small rectangular slot in said insulating member, and the arcuate slot in said end cap, and means to fasten said metallic grounding cap, said insulating member and said end cap together in such a manner whereby said metallic grounding cap and said end cap will not be short circuited.
2. In a plug connector, a handle of insulating material having a central opening to receive an extension cord, a metallic grounding cap having a central opening therein and opposed arcuate slots therein, means to connect said handle and said cap, an insulating member having arcuate troughs extending part way therethrough, small rectangular slots extending all the way therethrough, a central opening extending therethrough and also arcuate shoulder portions adjacent said cap, said shoulder portions extending within the arcuate troughs in said cap, an end cap having arcuate slots adjacent said insulating member, an electrical connector for joining one terminal of said extension cord to said metallic grounding cap, a second electrical connector for joining the second terminal of said extension cord to said end cap, said second connector being in contact with the end cap and having a portion extending through an arcuate slot in said metallic grounding cap, through the small rectangular slot in said insulating member, and through the arcuate slot in said end cap, and means to fasten said metallic grounding cap, said insulating member and said end cap together in such a manner whereby said grounding cap and said end cap will not be short circuited, said means comprising an insulating tube and bolt means extending through the tube.

3. In combination with an electrical socket having spring clips to which current is extended and a casing which is grounded, a plug connector comprising a handle of insulating material having a central opening for receiving an extension cord, a metallic grounding cap of sufficient diameter to engage said casing of said socket, a cylinder of insulating material for connecting said grounding cap and said handle, an electrical connector for joining one of the terminals of said extension cord to said grounding cap whereby said terminal is grounded, an insulating member over-

lying said grounding cap, a metallic end cap overlying said insulating member, a second electric connector in contact with the end cap, said metallic grounding cap and said insulating member and said second connector and said end cap having aligned central openings therethrough, an insulating tube extending through said openings, bolt means extending through said tube and securing the insulating member, the end cap and the second electric connector to the metallic grounding cap while the end cap is insulated from the metallic grounding cap, said second electric connector having a prong extending through the metallic grounding cap but insulated therefrom by said overlying insulating member, said end cap being of sufficient diameter to engage said

spring clips of said socket, and an electrical connection between the second terminal of said extension cord and the prong of the second electrical connector that is connected to said end cap.
